UNITED STATES PATENT OFFICE.

WILLIAM C. EDGE, OF MONTROSE, NEW JERSEY.

BUCKLE FOR REINS.

SPECIFICATION forming part of Letters Patent No. 487,474, dated December 6, 1892.

Application filed June 13, 1892. Serial No. 436,464. (No model.)

To all whom it may concern:

Be it known that I, WILLIAM C. EDGE, residing at Montrose, Essex county, in the State of New Jersey, have invented an Improved Buckle-Holder for Reins and other Purposes, of which the following is a specification, reference being had to the accompanying drawings, forming part thereof, wherein—

Figure 1 represents a top view of my improved buckle-holder. Fig. 2 is a longitudinal section of the same on the line 2 2, Fig. 1; and Fig. 3 is a cross-section of the same on the line 3 3, Fig. 2.

This invention relates to improvements in rein-holders for controlling spirited horses; but it is also applicable in its main feature to other purposes.

The invention consists in the new arrangement and combination of parts hereinafter more fully described.

In the drawings the letter A represents a rein. Ordinarily in driving horses two reins are used, which are united at or near their ends by a buckle. Hence one of the reins carries a buckle and the other has its end perforated to fit such buckle. To reins such as these I propose to attach my improved buckle-holder, which therefore must be of such a kind that the buckle at the end of one of these reins can pass through it. Otherwise the buckle-holder could not be applied.

My buckle-holder B consists, mainly, of a rectangular frame having a loose and wholly-disconnected cross-bar a, provided with a shoulder x near each end thereof. This cross-bar may or may not also carry a buckle-pin b, which is adapted to pass through the strap or rein. Fig. 3 clearly shows the cross-bar a to be loose and disconnected from the frame B of the buckle-holder. The frame B of the buckle-holder also when used for reining horses is provided with a grip-handle d, which is a curved projection shaped to fit the hand, so that a rigid grip on the reins may be obtained.

In operation the rein A, whether it carries a buckle or not, can be drawn through the buckle-frame B with great ease, because while drawing it through the cross-bar a can be entirely lifted off or even taken out, and afterward said cross-bar, being drawn down, is held in its position, as indicated in Figs. 2 and 3, solely by the pressure of the strap, the transverse movement of the bar or the twisting thereof being prevented by the shoulders thereon, which engage the inside of the buckle-frame, as shown in Fig. 3. So it will be seen that the cross-bar a will act as a buckle-bar, jamming against the strap in the direction from which pressure is applied, thus keeping the buckle-frame on the desired part of the rein, even though said cross-bar has no pin b, it being observed that the cross-bar a when pressure is applied to either end of the rein or strap will move with it a sufficient distance on account of its sliding capacity to jam and hold the buckle-frame.

What I claim is—

1. The combination of the buckle-frame B and wholly-disconnected longitudinally-movable cross-bar a, having shoulders x, said cross-bar being adapted to slide on said buckle-frame in the direction from which pressure is applied and being prevented from twisting or from transverse movement by the shoulders x, substantially as described.

2. The combination of the buckle-frame B, wholly-disconnected longitudinally-movable cross-bar a, having shoulders x, which engage with the buckle-frame when the parts are in operative position, and handle d, said cross-bar a being adapted to jam against and secure the strap within said buckle-frame, substantially as described.

WILLIAM C. EDGE.
